UNITED STATES PATENT OFFICE.

WILLIAM HAMMOND LEISTER, OF WESTMINSTER, MARYLAND.

CAN-LABELING MACHINE.

SPECIFICATION forming part of Letters Patent No. 659,075, dated October 2, 1900.

Application filed July 29, 1899. Serial No. 725,481. (No model.)

To all whom it may concern:

Be it known that I, WILLIAM HAMMOND LEISTER, of Westminster, in the county of Carroll and State of Maryland, have invented 5 a new and Improved Can-Labeling Machine, of which the following is a full, clear, and exact description.

My invention relates to an improvement in devices for applying labels to cans, and comprises the novel features hereinafter described and claimed.

Reference is to be had to the accompanying drawings, forming a part of this specification, in which similar characters of reference indicate corresponding parts in all the views.

Figure 1 is a side elevation of one end of the machine. Fig. 2 is an elevation from the same side of the other end of the machine, the two figures joining, respectively, upon 20 the right and left margins thereof. Fig. 3 is a side elevation of the extended portion of the can-rack, which is broken away at the right of Fig. 2. Fig. 4 is a top plan view of the mechanism which is placed above the can chute or track. Fig. 5 is a top plan view of 25 the can chute or track. Fig. 6 is a longitudinal sectional elevation of the can chute or track and the mechanism for applying adhesive material to the can and label. Fig. 7 is a top plan view of the tank and mechanism 30 which applies adhesive material to the can in order that it may take up a label, the cover of the tank being removed. Fig. 8 is a side elevation of the upper end of the frame carrying the paste-reservoir P and the belt by which 35 the paste is applied to the labels. Figs. 9 and 10 are elevation and plan views of the can-receiving table, which is broken away at the left of Fig. 1. Fig. 11 is a cross-sectional elevation taken through the can chute or track, showing the method of adjusting the same laterally; and Fig. 12 is a cross-sectional elevation of said chute or track, taken through 40 the sockets which contain the label-holding 45 hooks.

This machine belongs to that class in which the cans are rolled along a chute or track and are successively operated upon, whereby a portion of the adhesive material is applied to 50 the can, and the can is then rolled upon a pile of labels, picking up the upper label by said adhesive material and then wrapping the

label about the can, the other end of the label being pasted so that as it is wrapped about the can it will be secured in place.

55

The main bar A of the framework extends substantially in the same direction and parallel with the tracks upon which the cans roll. This bar is supported upon bars A⁴ and A⁶, located at each end thereof, said bars being supported from a low table or frame consisting of bars A' and the legs A², said frame being braced by means of diagonal braces A³. At each end of the bar A and at such other points as may be found necessary are provided supports for the track-bars B, said supports being constructed after the manner shown in section in Fig. 11. The bars B, forming the track or chute, have laterally-extending pins or bars b, secured thereto and 60 extending into sockets B⁴, formed within posts B³, placed upon the frame-bar A. The socket B⁴ is larger than the pin b and receives a spirally-coiled spring b', which surrounds the pin b. This spring serves to force the track-bar B away from the frame-bar toward the center. This action is resisted by means of a thumb-nut b², which screws upon the outer 65 end of the pin b. As many of these supporting-pins as are necessary are provided. I 70 have herein shown two for each bar, one located at each end thereof. The bars B serve simply to support the cans. The cans are guided in the proper course upon the track-bars by means of bars D, which are supported 75 above and outside of the track-bars, being adapted to engage the ends of the cans and restrain them against side motion. These bars are also made adjustable in a manner somewhat similar to that used for the track-bars B. The bars D have lateral projecting pins D', which pass through holes in posts or brackets D³, which extend upwardly from the frame-bar A. This permits movement of the bars D transversely of the track. The bars 80 are secured in adjusted position by means of set-screws D², which pass through the upper ends of the brackets or posts D³ and engage the pins D'. By the means described the 85 track and the restraining-bars D may be adjusted for any ordinary-sized can.

90

95

100

The cans are fed to the chute or track just described by means of receiving-tracks, which are located at one end and above the ma-

chine. For convenience and to keep the machine within reasonable limits this receiving-track has been made into two sections, one located above the other, both sections being inclined, but in opposite directions. The lower section E' is secured to one end of the frame-bars A at E⁵ and is supported by means of a brace-rod E⁶, which at its upper end is pivoted to bars E', forming the lower portion 10 of the receiving-track, and at its lower end is adapted to engage the frame of the machine in any convenient manner, as by entering a socket or hole formed in said frame. The upper section E of this track is supported on 15 the lower section by means of bars E³ and E⁴. The outer ends of the bars E', forming the lower section, are curved upwardly, as shown at E² in Fig. 3. The space between the outer end of this bar and the corresponding end of 20 the bar E is sufficient to permit a can to pass between. The cans are placed upon the upper section, as indicated by dotted lines in Fig. 2, and roll down the same until they come to the opening between the ends of the bars 25 E and the curve E², when they drop to the lower section and pass down upon the same to the can-chute upon the machine. As they strike this can-chute they are engaged by the feed-wheels H². These wheels are preferably 30 provided with a rubber band or covering, which will engage the cans. The wheels H² are mounted upon the ends of a transversely-extending shaft H', which is journaled within the outer or swinging end of a link or bar H, 35 the other end of such link or bar being pivoted upon a transversely-extending shaft a', which is placed in the upper end of a standard a, supported upon the frame-bar A.

To the standards a are secured two arms 40 H⁷, which extend in opposite direction therefrom and longitudinally of the machine. On the outer ends of these arms are secured vertical bars H⁸ by means of set-screws h⁶, which pass through slots in said bars, so that the bars H⁸ are adjustable in elevation. The upper ends of these bars engage, respectively, 45 the link or bar H and a corresponding link or bar h, which extends oppositely from the bar H. By adjusting the bars H⁸ the links H and h are raised or lowered and the wheels carried thereby adjusted to correspond with the different-sized cans. These links or bars H and h are held downward by gravity and by 50 the action of a flat plate-spring H⁶, which at 55 its central point is secured to a bar connecting the upper ends of the standards a. The link h, which forms the frame carrying the wheels h², is pivoted upon the same shaft a' as that carrying the link H. Each, however, 60 extends in an opposite direction. The wheels h² are similarly provided with rubber bands or tires about their peripheries, so that they will engage the cans without slipping.

Keyed upon the shaft a' are two grooved 65 pulleys H⁴ and h⁴. Upon the shaft H' is also secured a grooved pulley H³, which is in line with the pulley H⁴. About these two pulleys

passes a belt H⁵, so that the two shafts are turned together. The shaft h' also has a grooved pulley h³ secured thereto and a belt 70 H⁵ passing about the same and the grooved pulley h⁴. The sizes of these pulleys are such that the shaft h' and the wheels carried thereby are rotated much more rapidly than the shaft H' and the wheels carried thereby. The 75 wheels h² are accelerating-wheels, being designed to engage the cans and accelerate their rolling movement upon the can chute or track. Cans coming down the inclined track E' will 80 first engage the wheels H² and will be fed beneath the same at a rate corresponding with the speed of the rotation of the said wheels. These wheels, therefore, act as regulating and feed wheels, determining the rate of feeding the cans. 85

While passing beneath the wheels H² the can is operated upon by a device which applies a small amount of cement or adhesive material to the can, so that the can may be enabled to secure one end of the label thereto 90 when it rolls upon it. The tank F, which contains the adhesive material, is located beneath and between the frame-bars A and the track upon which the cans roll. This tank is shown in cross-section in Fig. 6. It is made 95 with one end a little lower than the other, so that the cement or adhesive material contained therein will flow toward this end and make it possible to more nearly use up all the material in the tank than would be possible if the bottom of the tank were level. Within the tank is pivoted a lever or frame g by means of a pivot g', located at the end of the tank where the bottom is highest. This frame carries two spring-wire arms g², upon 100 the outer ends of each of which is placed a pad or small hammer g³. Near the opposite or lower end of the tank is pivoted a lever G⁴, one end of which passes beneath the frame g, so that when the opposite end of the lever G⁴ is depressed the frame g will be raised, 105 carrying upward the pads g³. Upon the short end of the lever G⁴ is secured a plunger-rod, which is made in two parts, consisting of sections G and G', the lower section 110 G' being pivoted to the end of the lever G⁴ and the upper section G passing through the hole f' in the cover F² of the tank. The adjacent ends of these two sections are reduced in size and a spirally-coiled spring G² is 115 placed about the same. This spring will normally hold the two sections separated and make the device yielding, so that the bars need not be adjusted as accurately in their movement as would otherwise be necessary. 120 The power for depressing this plunger is mainly derived from the wheel H², acting through the can. The cover F² of this tank is preferably made slightly concaved on its upper side, so that any cement or paste which 125 may drop thereon will flow to the center. The cover is also inclined in the other direction and is provided with a slot f² near its lower end, through which the cement or paste

which may collect upon the cover may flow back into the tank. The cover is also preferably provided with a flange F^3 , extending about its edge and preventing the escape of any cement from the edges of the cover. The spring-arms g^2 , which carry the pads g^3 , are guided laterally by means of ribs f^3 , placed within the tank. The cover F^2 of the tank is provided with two holes f , located 5 one at each side thereof and so placed that the pads or hammers g^3 when they rise by reason of the depression of the plunger G will be projected through these holes, and thus come in contact with the lower side of 10 the can which has just passed over and depressed the plunger G . The upper end of the plunger ordinarily projects above the track, so that the can as it passes down the track will depress the plunger and cause the 15 pads g^3 to be raised into contact therewith, thus placing two small spots of cement or adhesive material upon the outer surface of the can. The tank is made readily removable from the frame in order that it may be 20 filled when necessary. On its lower side it is provided with one or more longitudinally-extending flanges F' , which fit within grooves formed in a plate F^6 , which is supported from the frame-bar A by means of the bars F^4 , located 25 one at each side thereof. The tank is clamped in position by means of set-screws F^5 , which pass through said bars F^4 and engage the outer surface of the tank.

The tank F is kept heated by means of a 30 torch T or any other suitable device located beneath the same. The torch herein shown is of that general type which uses gasolene or similar fuel and compressed air for forcing the same to the burner. This form of torch 35 is in common use by electrical workers. The tank T' of said torch is held in place upon a stand T^2 by means of a set-screw T^3 , which engages one side thereof, the other side being held by a flange upon the stand. This 40 stand is supported by a bar T^4 from the lower frame-bar A' .

The labels L are placed in the machine in a large bundle or pile. These labels are supported upon a plate C , which in turn is carried 45 by posts C' , which are mounted to slide in suitable guides in the framework. The plate C in its depressed position is adapted to lie upon the plate C^3 , which forms a portion of the framework. This plate C^3 is supported 50 upon bars A^7 , which at their lower ends are secured to the frame-bars A' . The plate C^3 is also connected with the upper frame-bar A by means of bars A^8 , which pass upward alongside of the labels. The labels are 55 restrained in position upon the label-plate C by means of the bars A^9 , which at their upper ends are secured to the inner edges of the track-bars B' by being notched into the same, so that the outer surfaces of the bars 60 A^8 and the track-bars B' are flush, as shown at A^9 in Fig. 5. The lower ends of the bars A^9 are connected by a transverse member,

which has a central depending arm U , the lower end of the arm being bent horizontally and projecting toward one side of the machine. This lower portion of the bar or extension U is slotted longitudinally or in a direction transversely of the machine, and it is secured to the plate C^3 of the frame by means of a bolt and clamping-nut, whereby 70 it is made adjustable transversely of the machine to correspond with labels of different widths. The ends of the labels are kept in correct position by means of a bar C^4 , which extends upwardly from the end of the plate C^3 to near the top of the pile of labels. The lower ends of the posts C' which support the label-plate are connected by a cross-bar or plate C^2 , which is connected with a link C^6 , the other end of the said link being pivotally 75 connected to the outer end of the spring-bar C^5 . The opposite or fixed end of the spring-bar C^5 is secured to an arm C^9 , which projects downwardly from the frame and is rigidly secured thereto. This spring is of such strength 80 that it will support the pile of labels and force the label-plate, with the labels thereon, upwardly, so as to keep the top of the pile in a fixed position. When the spring is in its lowermost position, as when a pile of labels 85 has been just placed in the machine, it is exerting the most strain, which is required, as the weight of the labels is the greatest at this point. As the labels are consumed their weight decreases, and the strength of the 90 spring correspondingly decreases as it is moved upward, which is due to the consumption of the labels. The tension of the spring may be adjusted by means of a bar C^7 , which is secured by a screw or bolt C^8 to the lower 95 portions of the arm C^9 . The lower portion of this bar, through which the screw C^8 passes, is provided with a slot receiving the screw C^8 , so that the bar may be adjusted to contact the upturned end thereof with the spring C^5 at different distances from its support, thereby varying 100 the tension of the spring. The labels are limited in their upward position by means of a roller L' , which is journaled in the frame-bars A and which extends across one end of 105 the labels. The labels contact with the lower edge thereof near their ends. This roller prevents the labels from rising too high and also enables the labels to be easily pulled from beneath the same as they are attached 110 to the cans. The can after having a small amount of adhesive material or cement applied thereto by the mechanism contained within the tank F rolls downward upon the track or chute until it drops upon one end of 115 the pile of labels, said end being the free end, or the one opposite that which is held down by the roller L' . The distance between the point where the cement has been applied to the can and the point where it drops upon the 120 labels is such that the can has made one complete revolution. It will therefore drop upon the labels with the spotted side or that containing the cement downward. The label 125

will therefore be well attached to the can, so that as the can continues its forward movement the label will be wrapped around the can. The track at this point is provided with a drop, as shown at V in Fig. 6. The point where this drop commences is varied by means of a slide v, which consists of a plate forming a short section of the track and provided with a slot v', through which passes a clamping-bolt v². The end of the plate v from which the can drops is curved downwardly, as shown at v³. The label having been attached to the can and rolled about the same passes beneath a smoothing device consisting of a spring-plate M', which is supported from standards M, secured to the frame of the machine at such a height that it will lightly engage the upper side of the can as it rolls beneath. At about the time the can drops into the depression V in the track it is engaged by the accelerating-wheels h², so as to cause it to move more rapidly along the track. This insures also that it shall be forced into the depression V in the track, and thus be brought into contact with the labels. At a point near the roller L' two sockets are provided in the track B, one upon each side of the machine. These sockets contain a block b³, which is provided with a hook-arm b⁶, projecting toward the center of the machine. The sockets are open at their inner edge or provided with a slot adapted to accommodate said hook-arms. Blocks b³ are held down by means of a spiral spring b⁴, which in turn is held by a threaded lug b⁵, which screws into the upper end of the socket. These hook-arms lightly engage the upper label of the pile near its edge and prevent the same from being removed without the application of a little force. As the label is wrapped about the can the can will in its forward movement break the label from beneath the hooks, thus making a slight tear in the edge of the label. If this is deemed undesirable, the hooks may be rounded at their points, so that the label will be pulled from beneath the same without tearing. Just before the label is removed from the pile the end thereof is coated with paste, so that when it is wrapped about the can it will stick in place. The means for applying the paste is shown in Figs. 1 and 6, Fig. 6 being a section thereof. A standard A⁶ forms a portion of the framework of the machine and is curved so as to receive the paste tank or reservoir P. This tank or reservoir has an arm P' upon each end thereof curving upward and backward and slotted at its end. Said arm is adapted to slide between two guideways a⁶, placed upon the side of the standard A⁶. A clamping-bolt a⁵ passes through the slot in the arm P' and secures the bar to the standard. The frame is secured by or formed as a part of the paste-tank, said frame containing the standards P², to the upper ends of which are secured the bars P³, which extend at an angle to the horizontal, the upper end thereof extending to very near the roller

L'. In the upper outer end of the bar P³ are formed two bearings adapted to receive the journals of two rollers O² O³. The bearing for the journal O² consists of a notch extending inward from one edge of the bar, so that the roller O² may be readily removed therefrom when desired. The bearing for the other roller O³ consists of a vertical slot, whereby the roller is permitted to have a limited vertical movement. Within the paste tank or reservoir P is journaled a roller O', and a fourth roller O is journaled upon the bar P³ above the tank. About these various rollers passes a belt p, which dips beneath the paste in the tank and thus becomes coated. This belt passes about the roller O³ as a loop and passes above the roller O², said roller O² simply engaging the outer surface of the belt. This leaves a short section of the belt at p' in position to be engaged by the upper surface of the uppermost label in the pile. The roller O³ is located immediately above the end of the pile of labels. Depending from the bar P³ of the frame is an arm P⁵, to the lower end of which is pivotally secured a fork R, the two prongs of which extend upon opposite sides of the belt and act as a scraper to remove surplus paste from the belt. This fork is secured in position by means of a clamping-bolt or set-screw R'. The fork may thus be adjusted by twisting on its pivot, so as to bear lightly or hard upon the uprising section p² of the belt, as may be desired. The roller O is provided upon one end with a ratchet-wheel O⁵, which is adapted to be engaged by a pawl Q' to turn the same. This pawl is pivoted upon one end of a lever Q, which in turn is pivoted at Q³ upon the main frame of the machine. The pawl Q' is held in contact with the ratchet-wheel by means of a counter-weight Q² upon its upper end. The lever Q is vibrated to turn the ratchet-wheel O⁵ by means of a link K², which is operated in a manner hereinafter to be described. After the can has passed beneath the smoothing-plate M' it is engaged by a belt I⁴, which passes over two drums I² and J'. These drums are mounted above the track in a common frame I. This frame I is mounted to swing upon a shaft J, which forms a shaft for the drum J' to turn upon. The drum I² is mounted upon a shaft I', which turns in the outer end of the frame I. The drum I² drops downward under the influence of gravity and is limited in its downward drop by having a projection upon one side of the frame I engaged with the upper end of a post or standard K, projecting upwardly from the main frame of the machine. The swinging frame I is also held downward by means of a spring K', which is secured to the standard K and the frame I. The belt I⁴ is an elastic belt of rubber or similar material, so that as the can passes beneath the same it will press firmly upon the entire surface of the can, even if it should happen to be somewhat irregular in outline by having been dented, and it

will thus insure that the label be smoothly pressed to the surface of the can. Upon one end of the shaft J is secured a gear-wheel N', which meshes with a pinion N, 5 mounted upon a shaft N³, which is supported upon the outer end of an arm I³. Upon the shaft N³ is also secured a fly-wheel N², by which means the rotation of the mechanism may be made smoother and more regular than 10 if unsupplied with a fly-wheel. Upon the other end of the shaft J is secured a crank J³, by means of which the shaft may be turned. In lieu of the said crank a pulley may be provided, upon which a power-belt may be placed. 15 Upon the shaft J is also placed a grooved pulley or wheel J², which is in line with a similarly-grooved wheel J⁵, placed upon the shaft a' at the other end of the machine. About these two pulleys passes a belt J⁴, by 20 means of which power is communicated to the shaft J and to the mechanism at the other end of the machine. By arranging the paste-belt and pressure-belt with respect to each other and to the pile of labels, as shown, and 25 operating the paste-belt from the swinging frame carrying the pressure-belt the paste-belt will be moved at the time the label is being drawn by the can from under the paste-belt, and the belt and label moving in opposite 30 directions will cause the paste to be rubbed into the pores of the label, rendering it soft and permitting it to be firmly and smoothly pressed upon the can. The cans after being engaged by the belt I⁴ are rolled 35 beneath the same and the label securely smoothed upon the can. They then roll off of the track B upon the track composed of two channel-bars e, which are secured to one end of the machine. From these two bars 40 they roll upon the filling-table, which consists of a board e², and the edges of this board are provided with notches e³ of a size corresponding to the size of the cans, so that when 45 the board e² is filled with cans the notches e³ will lie immediately beneath the cans. This makes it easier to grasp the cans for removal than when the edges of the board are straight, as the can ends will lie directly over the notches. A stop is provided at the outer end 50 of the delivery-table and consists of a roller e⁴, supported at a slight elevation above the belt. This table is supported in position by means of a brace e', which is secured to the table and to the lower portion of the legs A². 55 Casters are provided on the lower ends of the legs A², as shown in Figs. 1 and 2, so that the machine may be readily moved about from one place to another, and thus be brought close to the pile of cans, thus facilitating the 60 operation of labeling.

In order to move the machine about conveniently, handles S are secured to the framework at convenient points.

An alarm device is provided which will 65 give notice when the labels are about exhausted, said alarm device being shown in Fig. 1.

To the lower side of the plate or bar C³ is secured a bent arm W², upon which is mounted a bell or gong W'. The spring-arm, which 70 carries the hammer W³, is secured to the arm W² and is normally held raised above the gong by means of a hook-bar W, which is pivotally secured to the lower portion of the bar or plate C³ or to the arm W², as desired. 75

As the label-plate C rises, due to the consumption of the labels, the cross-bar C², which connects the lower end of the post C', rises with it, and a pin W⁴, which is secured thereto, rises until it engages with the hooked bar W 80 to move the same to one side and free the spring-hammer arm, allowing it to fall upon the gong and sound the alarm.

As the cans pass beneath the drum I² it is slightly raised, but drops back as the can 85 passes from beneath it. This acts through the connection of the link k² with the frame I and lever Q, to turn the ratchet-wheel O⁵ and the pasting mechanism. For convenience in putting in place a new supply of labels a device for holding down the label-plate C is provided. From beneath the plate or bar C³, which forms a part of the frame, depends a rod X, which has its lower end enlarged, as shown at X'. This rod passes through a hole 95 in the cross-bar C², which moves with the label-plate. When the label-plate is forced downward sufficiently, the lower end of this rod will clear the bar C² and engage its upper surfaces, holding the label-plate down until 100 it is freed by hand. From the point where the end of the label is pulled clear of the roller L', the can makes a half-turn before reaching the large roller or drum J', which thus brings the ends of the label beneath and 105 in contact with the drum, causing the label to be seamed by the pressure of the elastic belt and the drum thereon. The springs Y, which form that portion of the track just beneath this drum, will give to allow the cans 110 to pass beneath the drum. This drum is used particularly to seam the label and might be called a "seaming-drum".

Having thus described my invention, I claim as new and desire to secure by Letters 115 Patent—

1. A can-feeding mechanism for can-labeling machines and the like, comprising two superimposed and oppositely-inclined tracks adapted to convey the cans, the upper end of the lower track curving upward above the lower end of the upper track and at such distance therefrom as to permit the cans to pass between the two, and a can checking and feeding wheel engaging the cans upon the 125 lower track and prior to engaging any part of the labeling mechanisms to regulate their rate of feed.

2. A can-feeding mechanism for can-labeling machines and the like, comprising two superimposed and oppositely-inclined tracks adapted to convey the cans, the upper end of the lower track curving upward above the lower end of the upper track and at such dis-

- tance therefrom as to permit the cans to pass between the two, a can checking and feeding wheel engaging the cans while upon the lower track and regulating their rate of feed, and a 5 swinging frame carrying the journals for said wheel and permitting it to be raised by the can.
3. A can-labeling machine comprising label-supporting mechanisms, a can - conveying 10 track extending above the labels, said track having a depression or drop over one end of the labels, and a longitudinally-adjustable track-section at the approach end of said depression or drop, whereby the length of the 15 depression and the point of dropping the can may be regulated.
4. A can-labeling machine comprising label-supporting mechanisms, a can - conveying 15 track extending above the labels, said track having a depression or drop over one end of the labels, a longitudinally-adjustable track-section at the approach end of said depression or drop whereby the length of the 20 depression and the point of dropping the can may be regulated, mechanism for applying 25 cement to the cans before reaching said depression, and means for adjusting said mechanism along the track.
5. A cement-applying means for can-labeling 30 machines, comprising a cement - tank placed below the can chute or track, pivoted arms carrying cement-conveying pads at their outer or swinging ends adapted normally to lie in the cement and to be raised into contact with the cans as they pass over the track, 35 a lever engaging said arms to raise them, a two-part plunger, one part connected with said lever and the other projecting in the path of the cans, and a spring connecting the 40 two parts, whereby a yielding pressure is applied to raise said pads.
6. A can-feeding device for labeling-ma- 45 chines and the like, comprising a chute or track, a vertically-swinging frame carrying a feed-regulating wheel engaging the cans, means for turning said wheel to feed the cans forward, a vertically-swinging can-acceler- 50 ating wheel engaging the cans after passing the regulating-wheel, and means for turning said accelerating-wheel at a higher peripheral speed than the regulating-wheel.
7. A can-labeling machine, comprising a 55 chute or track, means for presenting the labels from beneath the track so that the cans will engage one end thereof, means for applying an adhesive material to the cans before reaching the labels, a spring-plate engaging the periphery of the can to smooth the label thereon before its other end is pasted 60 down, and means for applying an adhesive material to the other or free end of the label before it is wound upon the can.
8. A can-labeling machine comprising a can 65 chute or track having an opening in its bottom adapted to receive the labels, a label-plate movable on vertical guides toward and from said opening, a bar-spring fixedly sup- ported at one end and having its other end pivotally connected with the label-plate to raise it, and means for adjusting the tension 70 of said spring.
9. A can-labeling machine comprising a can chute or track having an opening in its bottom adapted to receive the labels, a label-plate movable on vertical guides toward and from said opening, a bar-spring fixedly sup- 75 ported at one end and pivotally connected with the label-plate to raise it, and an adjustable arm adapted to engage said spring at various distances from its support to adjust its tension.
10. A paste-applying means for labeling-ma- 80 chines comprising means for supporting a pile of labels, a paste-reservoir at one side of and beneath the labels a roller in said reservoir, a belt passing about said roller, guide-rollers for said belt, comprising two rollers located one above the end of the pile of labels and the other adjacent and upon substantially the same level, the belt passing 85 about the first of said two rollers and above the other, and means for causing the belt to travel over said rollers.
11. A label-pasting device comprising a 90 paste-reservoir having a roller therein, a belt 95 passing over said roller, guide-rollers for said belt adapted to present a belt-section for contact with a label presented from below, means for moving the belt over the rollers, a pivotally-supported two-tined fork, the tines 100 thereof engaging the opposite sides of the belt as it comes from the paste, to remove the surplus paste, and means for presenting the labels from below to engage their ends with said belt.
12. A label - pasting device comprising a 105 belt, rollers supporting the same and passing the belt beneath the surface of the paste, and a scraper for said belt, consisting of a pivotally-supported two-tined fork having one tine 110 upon each side of the belt and engaging the edges thereof to scrape off the surplus paste.
13. A label-pasting device for labeling-ma- 115 chines, comprising a removable paste-reservoir, a roller journaled in the lower portion 120 of the reservoir, a frame carried by the paste-reservoir and projecting above the same, said frame having an inclined upper portion extending beyond the reservoir, a roller journaled in the inclined portion of the frame 125 over the reservoir, two rollers journaled in the inclined portion of the frame extending beyond the reservoir, one in front of the other, and a belt passing over said rollers, substantially as described.
14. In a label-machine, the combination 130 with a supporting-frame, of a paste-reservoir, means for detachably securing the paste-reservoir to the frame, a roller journaled in the paste-reservoir, standards secured to and projecting above the paste-reservoir and provided at their upper ends with inclined bars projecting beyond the paste - reservoir, a roller mounted in the inclined bars over the 135

paste-reservoir and provided with a ratchet-wheel at one end, two rollers mounted in the projecting ends of the inclined bars, one in front of the other, a belt passing around said 5 rollers, and means for operating the ratchet-wheel, substantially as described.

15. In a can-labeling machine, a chute or track having an opening in its bottom, and sockets in the chute or track at each side of 10 the opening, said sockets having slots in their inner sides, means for supporting a pile of labels in said opening, and spring-pressed hooks in said sockets and extending outward through the slots of the sockets over the 15 labels, substantially as described.

16. A can-labeling machine having a can chute or track provided with a hole in its bottom adapted to receive the labels, means for supporting a pile of labels in said hole with 20 their tops at a constant level, sockets or guides formed in the rail at each side of said hole and near one end of the label-pile, said sockets opening at their inner sides, a block sliding in said socket and having a hook-arm 25 extending outward and over the labels, a spring holding said block down, and means for interposing an adhesive material between the opposite end of the label and the can as it rolls over the labels.

30. 17. A label-pasting device, comprising a frame provided with means for securing it in place on the frame of a labeling-machine, said frame having mounted thereon a paste-reservoir having a roller journaled therein and beneath the surface of the paste, a belt passing over said roller, guide-rollers for said belt journaled in the frame and presenting a section of the belt for engagement by the labels, the roller supporting the loop of the belt at the 35 point where it is engaged by the labels and being free to move vertically, and means for moving said belt over the rollers.

18. In a label-pasting device for labeling-machines, a removable paste-reservoir, a roller 45 mounted in said reservoir, standards secured to and projecting above the paste-reservoir and provided at their upper ends with inclined bars projecting beyond the paste-reservoir, the ends of the said bars being provided with 50 vertical slots and adjacent to said ends with L-shaped slots, a roller mounted in the inclined bars over the paste-reservoir, rollers mounted in the slots of the projecting portion of the said bars, and a belt passing over 55 said rollers, substantially as and for the purpose set forth.

19. In a can-labeling machine, the combination with a track or chute, and a cement-tank below the track or chute, of a frame pivoted 60 in one end of the tank and provided with arms having pads at their ends, a lever pivoted between its ends in the opposite end of the tank and having one member engaging the said frame to lift it when the lever is rocked, and 65 a plunger secured to the other member of the said lever and projecting into the path of the cans, substantially as described.

20. In a can-labeling machine, the combination with a bed or table, of a paste-applying belt mounted to travel in the direction of the 70 length of the table or bed and in an opposite direction to the travel of the cans, and having a section extending over one end of the pile of labels, a swinging frame above the bed or table and carrying a pressure-belt, 75 said frame projecting over the paste-applying section of the paste-belt, and means for operating the paste-belt from the swinging frame, as and for the purpose set forth.

21. In a can-labeling machine, the combination with a bed or table, and a paste-applying belt mounted to travel in the direction of 80 length of the table and in an opposite direction to the travel of the cans and having a section extending over the end of the pile of 85 labels, of a shaft above the table, or bed, means for operating the said shaft, a drum mounted on the shaft, a frame mounted at one end on the said shaft and having its free end projecting over the paste-applying section 90 of the paste-belt, a drum mounted in the free end of the frame, a pressure-belt passing around the said drums, a pawl-and-ratchet mechanism for operating the paste-belt, and a connection between the pawl-and-ratchet 95 mechanism and the said frame, substantially as described.

22. In a can-labeling machine, the combination with a bed or table, a paste-applying belt mounted to travel on rollers in the direction of length of the bed or table and in an opposite direction to the travel of the cans, and having a section extending over one end of the pile of labels, and a ratchet-wheel on one of the rollers over which said belt passes- 100 of a shaft above the bed or table, means for operating the shaft, a drum on the shaft, a swinging and spring-pressed frame mounted at one end on said shaft and having its free end projecting over the paste-applying sec, 110 tion of the paste-belt, a drum mounted in the free end of the frame, a pressure-belt for smoothing the labels, passing around the said drums, a lever pivoted between its ends to the bed or table, a counterbalanced pawl piv- 115 oted to one end of the lever and engaging the ratchet-wheel, and a link having its upper end loosely pivoted to the swinging frame, and its lower end pivoted to the end of the lever opposite that carrying the pawl, sub- 120 stantially as described.

23. In a can-labeling machine, the combination with a label-support, and means for feeding the same upward, of a bell, a spring-hammer, a pivoted hooked bar on a fixed support 125 and engaging the hammer to hold it raised, and a projection carried by the label-support and adapted to engage the pivoted bar to disengage it from the hammer, substantially as described.

WILLIAM HAMMOND LEISTER.
